UNITED STATES PATENT OFFICE.

ALBERT G. DAVIS, OF SCHENECTADY, NEW YORK, ASSIGNOR TO GENERAL ELECTRIC COMPANY, A CORPORATION OF NEW YORK,

FLASH-BOILER.

SPECIFICATION forming part of Letters Patent No. 789,414, dated May 9, 1905.

Application filed January 11, 1904. Serial No. 188,506.

To all whom it may concern:

Be it known that I, ALBERT G. DAVIS, a citizen of the United States, residing at Schenectady, in the county of Schenectady and State 5 of New York, have invented certain new and useful Improvements in Flash-Boilers, of which the following is a specification.

In boilers of the flasher type, which are subjected to a high degree of temperature to 10 effect the superheating of the steam, the superheating-coils, due to the intense heat, are subject to relatively rapid deterioration as compared to the heating and vaporizing coil or coils, resulting in occasional interruptions 15 of the operation of the boiler for the purpose of renewing the superheating coil or coils when the same become defective. In automobile steam systems the renewing of defective superheating-coils is not a matter at all 20 times feasible—as, for instance, when the machine is in operation on the road. In order not to render the boiler wholly disabled under such emergency, my improved boiler is provided with a novel coupling device, by means 25 of which the main coils can be connected directly to the steam-supply pipe leading to the engine, thereby cutting out the leaky superheating-coils from the steam-generating system. At such times as the superheating-coils 30 are disconnected the efficiency of the system is somewhat impaired; but the vehicle is operative, which is the main consideration.

In carrying out my invention I provide a flash-boiler comprising a main coil for heating 35 the feed-water and generating steam and a superheating-coil, together with a coupling-spider connecting said main coil with said superheating-coil and with the supply-pipe to the engine. Forming a part of the coupling 40 are means for placing the main coil in communication with the steam-supply pipe leading to the engine through said superheating-coil or independently thereof, as the condition of the boiler demands.

For a consideration of what I believe to be 45 novel in my invention attention is called to the accompanying description and claims appended thereto.

In the accompanying drawings, Figure 1 is a side elevation of a flash-boiler having my invention in one of its embodiments applied thereto. Fig. 2 is a vertical transverse section of the coupling-spider, taken on line 22 of Fig. 1. Fig. 3 is a vertical section of a portion of the spider, taken on line 33 of Fig. 50 2, showing the connections when the superheating-coil is in operation. Fig. 4 is a similar section showing the connections when the superheating-coil is cut out of operation, and Fig. 5 is a perspective view of a valve-plug. 55

Referring to the drawings, 1 represents a flash-boiler situated above the usual fire-chamber, containing a burner 2 and its vaporizer. The main steam generating and heating coil 3 and the superheating-coil 4 are shown in dotted lines in Fig. 1, and the superheating-coil is disposed below the main coil. In other words, the coils are arranged in sections. For connecting the main coil or coils with the superheating coil or coils and the latter with 60 the steam-supply pipe leading to the engine—that is, in series relation—a coupling-spider or connector 5 is employed. This spider is composed of a central enlarged portion 6, having tubular arms 7, 8, 9, and 10 connected in 65 the order named with the lower end 11 of the main coils, the lower end 12 of the superheating-coils, the upper end 13 of said latter coils, and with the supply-pipe 14, leading to the engine. The spider 5 is preferably, although 70 not necessarily, a drop-forging having bored arms, the bores thereof being suitably connected at their inner ends and are closed at their outer ends by screw-plugs. The outer ends of the arms are formed with threaded 75 bosses 15, having central apertures 16 communicating with bores of the arms, said bosses extending from the side of the spider opposite to that of the central enlarged portion 6. The bosses receive the ends of the coils, and 80 the latter are retained in place by means of differentially-threaded sleeve-nuts 17, as clearly shown in Fig. 2. The ends 11 12 13 of the coils and the end 14 of the steam-supply pipe are threaded to receive the sleeve-nuts, which, in conjunction with the interiorly- 85 90 95

threaded bosses, form differential joints, and to insure steam-tight fits packings 18 are seated in the bosses, upon which the ends of the coils impinge.

- 5 The inner ends of the bores of arms 7 and 10 communicate with each other, while the bore of arm 8 connects with the bore of arm 7, and the bore of arm 9 connects with the bore of arm 10, as shown in Figs. 3 and 4.
- 10 This arrangement of the bore is a convenient form of carrying out the object of the connector or spider. Communication between the bores of the arms may be controlled by an interchangeable valve and blank plugs 19 and 20, respectively, which are seated in transverse bores or depressions 21, formed in the enlargement 6, the lower end of the depressions or bores being preferably tapered to receive the taper of the plugs. The plugs are
- 15 retained by means of screw-plugs 22, that screw into the tapered bores or depressions. The valve-plugs 19, Fig. 5, are provided with a transverse slot 23, that is adapted to register with the bores of the arms for permitting communication between the bores. Blank plugs 20 are shaped like the valve-plugs, so as to be interchangeable therewith when it is desired to cut off communication between any of the bores. However, it is not necessary to provide blank plugs, as the valve-plugs may be employed for cutting off communication between any of the bores simply by turning the latter plug so as to have its slot extend transversely to the bore of the arm. As shown in Fig. 3, the
- 20 blank plug prevents communication between the bores of arms 7 and 10, while the slotted valve-plugs permit communication between the bores of arms 7 and 8 and those of 10 and 9, so that the coils of the boiler are in series relation and constitute the complete generating system for producing superheated steam. The main coil is supplied with water from a pump or its equivalent in the usual manner, and the saturated steam generated therein, 25 passes to the superheating-coils through the tubular arms 7 and 8. The superheated steam passes to the steam-supply pipe 14 through the arms 9 and 10 and the valve between the same. While this is the normal circulatory course of the steam in the boiler, with the coils in series relation, the steam from the main coil or coils can be caused to pass directly to the steam-supply pipe leading to the engine independently of the superheating-coils, as
- 30 when the necessity arises for cutting the latter out of service in case of accident. In order to cut out the superheating-coil, the blank plug 20 between arms 7 and 10 is substituted for a slotted valve-plug, and the slotted valve-plugs 19, between arms 7 and 8 and 10 and 9, are substituted for blank plugs, so that steam passes directly from the main generating-coil to the steam-supply pipe through the arms 7 and 10 and the intermediate slotted valve-
- 35 plug 19

The spider or connector 5 is located exterior of the shell or casing of the boiler, so as to be readily accessible for the purpose of interchanging the plugs.

Boilers equipped with my invention are particularly useful for automobile systems, wherein the high efficiency of the flasher type of boiler is desired, at the same time having means for insuring the system from being wholly disabled upon critical deterioration of the superheating-coils.

In accordance with the provisions of the patent statutes I have described the principle of operation of my invention, together with the apparatus which I now consider to represent the best embodiment thereof; but I desire to have it understood that the apparatus shown is only illustrative and that the invention can be carried out by other means.

What I claim as new, and desire to secure by Letters Patent of the United States, is—

1. In combination, a boiler composed of tubes arranged in sections and forming a single continuous passage, with a means for cutting out one of the sections.

2. In combination, a boiler composed of tubes arranged in sections and forming a single continuous passage, a burner situated at one end of the sections, and a means for cutting out a section adjacent to the burner.

3. In combination, a fire-chamber, a vaporizing-coil in which the flow of fluid is toward the fire-chamber, a superheating-coil located between the vaporizing-coil and the fire-chamber, a discharge-pipe for the coil, and a means for connecting or disconnecting the superheating-coil to and from the vaporizing-coil and the discharge-pipe.

4. In a boiler of the flasher type, the combination of a main steam-generating coil having a single passage, a superheating-coil, and a means for utilizing said main coil co-operatively with said superheating-coil or independently thereof.

5. In a flash-boiler, the combination of main coils in which liquid flashes into vapor, superheating-coils, means for connecting said coils in series to form a single passage, and means for controlling the operative relation of said coils.

6. In a boiler, the combination of main vapor-generating coils, superheating-coils, a coupling device connecting said coils, and means in said device for placing said coils in series connection or for cutting out of service said superheating-coils.

7. In a flash-boiler, the combination of a coil for heating the liquid and generating steam-vapor, a superheating-coil, a vapor-supply pipe, a coupling-spider, joints connecting the spider with the coils and vapor-supply pipe, and interchangeable plugs for controlling the operative relation of the coils to the vapor-supply pipe.

8. In a flash-boiler, the combination of a

main vapor-generating coil, a superheating-coil, a vapor-supply pipe, a coupling-spider connected with the coils and the supply-pipe, and interchangeable plugs adapted to be secured in said coupling-spider for controlling the relation of the coils to the vapor-supply pipe.

9. The combination, with a flash-boiler having a main vapor-generating coil and a superheating-coil and an inclosing shell, of a coupling-spider arranged exterior of the boiler-shell which is provided with tubular arms and a central enlarged portion, interchangeable plugs arranged in said central portion for controlling the connection between the coils, and screw-threads for retaining the plugs on their seats.

10. A boiler comprising a single coiled conduit, and means for connecting the discharge end thereof at an intermediate point and cutting out the intervening portion.

11. A boiler comprising a continuous conduit, and means intermediate the ends thereof whereby the discharge end may be connected nearer to the receiving end.

12. A boiler comprising sectional tubes

which are normally connected in series, and means for cutting out one of the said sections.

13. A boiler comprising sectional tubes which are normally connected in series, a burner which heats one tube more than the other, and means for cutting out said tube.

14. A boiler comprising a coil in which fluid flows in one direction, a coil in which fluid flows in the opposite direction, and means for connecting one coil with the discharge end of the boiler through the other coil or independently thereof.

15. The combination of a burner, with a boiler comprising a coil in which fluid flows toward the burner, a coil in which fluid flows away from the burner, means for connecting the coils to cause the fluid to flow successively through them, and means for cutting out one of the coils.

In witness whereof I have hereunto set my hand this 7th day of January, 1904.

ALBERT G. DAVIS.
